UNITED STATES PATENT OFFICE

167,948

COMBINED DISPLAY FIXTURE AND CONTAINER

Edward J. McKenna, St. Louis, Mo.

Application July 21, 1952, Serial No. 20,702

Term of patent 14 years

(Cl. D80—11)

To all whom it may concern:

Be it known that I, Edward J. McKenna, a citizen of the United States, residing at the city of St. Louis, State of Missouri, have invented a new, original, and ornamental Design for a Combined Display Fixture and Container, of which the following is a specification, reference being had to the accompanying drawing, forming a part thereof, in which:

Figure 1 is a perspective view of a combined display fixture and container embodying my new design, shown in closed position; and

Figure 2 is a perspective view thereof shown in open position.

I claim:

The ornamental design for a combined display fixture and container, substantially as shown.
EDWARD J. MCKENNA.
